WITNESS:

R. G. Thomas

INVENTOR.

BY Fred Brown

Victor J. Evans

ATTORNEY.

UNITED STATES PATENT OFFICE.

FRED BROWN, OF HAMILTON, ILLINOIS.

TRACE-HOOK.

1,338,610.

Specification of Letters Patent. Patented Apr. 27, 1920.

Application filed July 7, 1919. Serial No. 308,957.

To all whom it may concern:

Be it known that I, FRED BROWN, a citizen of the United States, residing at Hamilton, in the county of Hancock and State 5 of Illinois, have invented new and useful Improvements in Trace-Hooks, of which the following is a specification.

This invention relates to improvements in harness and the principal object of the 10 invention is to provide means for engaging the ends of the traces to support said traces when the same are not connected with the whiffle tree.

Another object of the invention is to provide means for supporting the before mentioned means and acting as a connection for the breeching straps, the back strap and the crupper strap.

The invention also consists in certain 20 other features of construction and in the combination and arrangement of the several parts, to be hereinafter fully described, illustrated in the accompanying drawings and specifically pointed out in the appended 25 claims.

In describing my invention in detail, reference will be had to the accompanying drawings wherein like characters denote like or corresponding parts throughout the several views, and in which:—

Figure 1 is a plan view of a portion of the harness showing my invention applied thereto;

Fig. 2 is a section on line 2—2 of Fig. 1; 35 Fig. 3 is a section on line 3—3 of Fig. 1; Fig. 4 is a face view of the metal plate; Fig. 5 is a view of one of the hooks.

In these views 1 indicates a plate made of any suitable metal and provided with 40 oblong slots 2 which are arranged adjacent the periphery of the plate. These slots are adapted to receive the ends of the breeching straps 3, the back strap 4 and the crupper strap 5. A pad 6 of leather or the like, 45 engages the lower face of the plate and this pad is made of the same shape as the plate and is provided with the four slots 7 which register with the slots 2 in the plate. The upper face of the plate is provided with a pair of parallel ridges 8 and 50 with an opening 9 between the ridges and centrally arranged in the plate. A substantially rectangular member 10 rests on the plate with its lower side edges placed between the ridges 8, and an elongated spring 55 plate 11 has its central part resting on said

member. The plate, the pad, the rectangular member and the spring plate are all held together by the pin 12 which passes through the hole 9 in the plate and other holes in 60 the member 10 and the spring plate 11. The upper face of the member 10 is provided with the side flanges 13 between which the spring plate fits. The ends of said member are rounded so as to receive the rounded 65 ends of the hooks 14 which are movably held against the member by the straps 15 embracing the sides of the member and having their ends overlapping the rounded ends of the hooks and secured to the hooks by 70 the pins 16. The straps and springs act as clamping means for holding the hooks with their rounded ends engaging the rounded ends of the member 10. Adjacent the hooked outer ends of the hooks 14 projections 17 are formed which act as finger-engaging means for the raising of the hooks. These hooks are made of such a length that 75 they will engage the upper face of the plate and the hooked ends are provided with flat- 80 tened portions 18 for resting upon said plate. The spring plate tends to hold said hooks with these flattened portions against the plate.

It will thus be seen that when the eyelets 85 19 on the ends of the traces are placed in engagement with said hooks the traces will be supported and thus there is no danger of said traces becoming entangled with other parts of the harness or being broken 90 by being stepped on by the horse. When the traces are to be used it is simply necessary to raise the hooks by engaging the projections 17 with the fingers and removing the traces therefrom. 95

It is thought from the foregoing description that the advantages and novel features of my invention will be readily apparent.

I desire it to be understood that I may make changes in the construction and in the 100 combination and arrangement of the several parts, provided that such changes fall within the scope of the appended claims.

What I claim is:—

1. Trace-supporting means for harness 105 comprising a plate having slots therein for receiving parts of the harness, a spacing member connected with said plate and having its ends concaved, a pair of hooks having rounded ends engaging the concaved 110 ends of the said member, straps embracing the sides of the member and pivoted to the

ends of the hooks, and a spring plate connected with the top of the member and having its ends engaging the hooks.

2. Trace-supporting means for harness comprising a plate having slots therein for receiving parts of the harness, a pad under the plate, a spacing member on the face of plate, a pair of hooks having their ends

abutting the ends of the member, means for clamping the hooks against said member, a 10 spring plate engaging the hooks and a pin connecting the plate, the member and the spring plate together.

In testimony whereof I affix my signature.

FRED BROWN.
